J. C. CALLAIS.
COIN CHANGING APPARATUS.
APPLICATION FILED JUNE 24, 1918.

Patented Jan. 11, 1921.

UNITED STATES PATENT OFFICE.

JULIAN C. CALLAIS, OF ST. LOUIS, MISSOURI.

COIN-CHANGING APPARATUS.

1,364,864.

Specification of Letters Patent. Patented Jan. 11, 1921.

Application filed June 24, 1918. Serial No. 241,556.

To all whom it may concern:

Be it known that I, JULIAN C. CALLAIS, a citizen of the United States, residing at St. Louis, State of Missouri, have invented certain new and useful Improvements in Coin-Changing Apparatus, of which the following is a specification, reference being had therein to the accompanying drawing.

My invention relates to improvements in coin changing apparatus and has for its object to provide a unit for dispensing a particular denomination of coinage, to be detachably secured to a coin changing machine of the well-known type which is carried by the belt or garments of its user.

In the drawings—

Figure 1 is a front elevation of a device embodying my invention in place upon the ordinary coin-changing machine (the latter being indicated in outline by dotted lines).

Fig. 2 is an end elevation of the same.

Fig. 3 is a transverse sectional view of the same taken on the line 3—3 of Fig. 2.

Fig. 4 is a fragmental view of the lower portion of the same in closed position.

Fig. 5 is a similar view of the same with the dispensing annulus in opened position.

As shown in the drawings, the usual apparatus worn by a conductor or other change-making user is of the general outline indicated by the dotted lines in Fig. 1, and numbered 10 in said view; the usual construction thereof comprising chambers 11 (for quarters) 12 (for dimes) 13, and 14 (for 5-cent coins). My invention is an attachment for this structure, consisting primarily of an auxiliary chamber 15 to hold coins (such as one-cent coins) for making change in denominations other than those provided for by the main dispensing-chambers.

The chamber 15 has the usual slotted cap 16, and is mounted on the chamber 14 by suitable attaching means such as the spring-clamp 17 (see Figs. 1, 2 and 3), a yoke 18 further providing against slippage. A base-plate 19 carries the ejector annulus 20 pivotally mounted at 21, and said base-plate 19 also carries the vertical plate 22 to which the toothed sector 23 is pivotally mounted at

24; the teeth of the sector 23 meshing with the toothed-plate 25, said plate 25 being mounted on the outer face of the annulus 20. A thumb-plate 26 extends outwardly from the sector 23 for manipulation by the user, downward pressure on said plate 26 serving to discharge the coins fed to the annulus 20 from the barrel or chamber 15, when the parts are in the relative positions shown in Fig. 5, and when in that position the flange 27 with which the annulus 20 is provided serves to hold back the column of coins in the chamber 15.

The annulus 20 is of such height as to receive only the number of coins (for illustration, five one-cent coins) as are to be dispensed at each operation; the bed-plate 18 being recessed as indicated by 28, to permit the group of coins charged therein to fall downwardly when the annulus 20 is thrown out of registration with the barrel 15, and to opened position.

This attachment is primarily of use where five-cent or ten-cent fares have been altered to odd-cent charges. The user having the old apparatus designed for making change only in multiples of five-cents can thus add a single unit enabling change to be made for six-cent or other odd-amount fares or charges.

The annulus 20 is normally maintained in alignment with the barrel 15 by means of the leaf spring 29.

Having thus described my invention, what I claim as new, and desire to have secured to me by the grant of Letters Patent, is—

1. In a money changing apparatus, an auxiliary unit comprising a coin receptacle, an ejector adapted to receive a plurality of coins from said receptacle at a single charge, and means for moving said ejector to discharge its content; in combination with means for detachably mounting said auxiliary unit on a money-changing machine.

2. Coin ejecting means for money changing apparatus, said means comprising a frame, an ejector member pivotally mounted thereon, a toothed sector mounted in a substantially vertical plane on said frame, and a toothed plate fixed in a substantially hori-

zontal plane on said ejector member and having its teeth in engagement with said sector.

3. In a money changing apparatus, an auxiliary unit comprising a coin receptacle, an ejector adapted to receive a plurality of coins from said receptacle at a single charge, and means for moving said ejector to dis-

charge its content; in combination with means for detachably mounting said auxiliary unit in operative location beside a money changing machine.

In testimony whereof I hereunto affix my signature.

JULIAN C. CALLAIS.
